HENRY C. MELVIN, OF COARSEGOLD, CALIFORNIA.

INTERNAL-COMBUSTION ENGINE.

1,257,958.

Specification of Letters Patent. Patented Feb. 26, 1918.

Application filed April 11, 1917. Serial No. 161,301.

To all whom it may concern:

Be it known that I, HENRY C. MELVIN, a citizen of the United States, residing at Coarsegold, in the county of Madera and State of California, have invented new and useful Improvements in Internal-Combustion Engines, of which the following is a specification.

This invention relates to an internal combustion engine, and particularly to a valve mechanism for the same.

The object of the present invention is to provide a simple, substantial, cheaply manufactured, easily-applied valve mechanism for opening the exhaust valve in an internal combustion engine and particularly a mechanism in which the cam shaft and the connected two-to-one gears usually employed may be entirely eliminated. Further objects will hereinafter appear.

The invention consists of the parts and the construction and combination of parts as hereinafter more fully described and claimed, having reference to the accompanying drawings, in which—

The figure is a side elevation, partly in section, showing the application of the invention.

Referring to the drawings in detail, A 30 indicates the cylinder of an engine, 2 the piston, 3 the crank shaft, 4 the connecting rod, 6 the spark plug, 7 the inlet valve and 8 the exhaust valve which, in this instance, will be operated by the mechanism which 35 forms the subject matter of the present application.

Secured upon the outer end of the crank shaft is a cam 9 and mounted in alinement with the cam and guided by bearing brackets 40 10 is a lifter rod 11. Mounted in alinement with the rod 11 and supported in a bearing bracket 12 is a second lifter rod 13 which engages the outer end of a rocker arm 14 pivotally mounted, as at 15, upon the cylinder and so positioned as to engage and operate the exhaust valve 8. Pivoted mounted, as at 16, in a collar 17 secured on the upper end of the rod 13 is an arm 18, and formed on the lower end of said arm is a projecting lug 19 which is adapted to serve as a filler or spacing block between the rods 11 and 13 as will hereinafter be described. Secured in one side of the cylinder is a valve cage 20 and slidably mounted in said cage is a rod 50 21 on the inner end of which is secured a

valve 22 while the outer end carries a collar 23 through which the arm 18 freely passes. The valve 22 is actuated by pressure within the cylinder and when so actuated moves outwardly in the direction of arrow *a*, in 60 this manner swinging the arm 18 about its pivot 16, thereby causing the spacing block 19 to move into alinement between the rods 11 and 13. Pressure formed by ignition of the combustible gases admitted to the cylinder swings the spacing block into position between the rods 11 and 13, while the spring 65 24, secured upon the collar 17, engages the arm 18 and forces it, together with the spacing block, the collar 23, the stem 21 and the 70 valve 22, inwardly or in the opposite direction. Secured on the upper end of the rod 11 and insulated therefrom is a contact member 25 and similarly secured on the inner side of the spacing block is a contact 75 member 26, which is connected through a wire 27 with the spark plug 6. A wire 28 is connected at one end with the contact 25 while the opposite end is connected with a battery or other suitable source of current 80 supply, not here shown.

The operation of the exhaust valve lifting mechanism will be as follows: The cam 9 is set in alinement with the webs of the crank shaft and will therefore assume its highest 85 position when the piston is up and its lowest position when the piston is down. Assuming that the piston has already drawn in a charge of combustible mixture and that the piston moves in an upward direction to 90 compress said charge, it will then be seen that the cam 9 will turn into a position where it will engage the roller 30 on the lower end of the rod 11 thereby lifting it, together with the rod, against the tension of 95 spring 31 in an upward direction. This upward movement will not affect the exhaust valve 8, as there is not sufficient pressure in the cylinder to force the valve 22 inwardly when the piston commences its 100 upward movement. The upper end of the rod 11 will therefore pass beyond the spacing block 19 and will therefore hold the arm 18 and the valve 22 in the position shown, while the piston travels upwardly to compress the charge. Sufficient movement of the valve is, however, permitted when the charge is compressed to move the arm into engagement with the upper end of the rod 11, thus causing the contacts to engage and 105 110

complete the circuit through the plug which will ignite the charge.

The piston will thus be driven in a downward direction and the cam will also travel to assume its lowermost position when the piston reaches the lowermost position, thus separating the rods to a point where the spacing block is permitted to enter, it being understood that the pressure of the burning gases is sufficiently great at this time period to force the valve against the seat and thereby move the spacing block into position between the rods. An upward movement of the piston will then take place and the exhaust valve will at the same time open to permit the escape of the gases, the lifting of the valve taking place when the cam forces the lower rod 11 upwardly, this upward movement being transmitted through the spacing block to the upper rod, which in turn lifts the rocker arm and opens the valve.

The valve will in this manner be completely open when the piston assumes its highest position, thus permitting a complete scavenging of the cylinder. It will, however, close the moment scavenging has taken place, as the drop in pressure within the cylinder will permit the spring 24 to swing the arm 18 back to pull the spacing block away from its position between the rods. The spring 32 on the exhaust valve will thus close the valve and force the rocker arm and upper rod back to normal position. The downward movement of the piston will then open the inlet valve by suction and thereby draw in a new charge which will again be compressed and the cycle of operation repeated.

The importance of the present mechanism can readily be appreciated when the following results obtained are considered: First of all, it permits the exhaust valve to be opened and closed without employing a cam shaft and driving gears. Secondly, it permits the exhaust valve to remain completely open until the piston has reached its uppermost position, thereby causing a more complete scavenging of the cylinder than can otherwise take place. Third, it permits the application of a simple ignition mechanism; and fourth, it can readily be seen that a much cheaper, more easily applied and fool-proof mechanism is permitted than would otherwise be the case.

A simple form of governor may also be employed, such as is generally indicated at 40, and I also wish it understood that the materials and finish of the several parts may be such as the judgment and experience of the manufacturer may dictate.

I further wish it understood that various changes in the form, proportions and minor details of construction may be resorted to within the scope of the appended claims,

and that I do not wish to limit myself to the specific design and construction here shown.

Having thus described my invention, what I claim and desire to secure by Letters Patent is:

1. In an internal combustion engine, a rotatable cam, spaced lifter rods slidably mounted and operable by the cam, an arm pivoted at one end to one lifter rod and extending alongside the latter, a spacing block carried by the opposite end of the arm for swinging from and to a position between the opposing ends of the lifter rods, and pressure controlled means for swinging the arm.

2. The combination with the exhaust valve on an internal combustion engine, the crank shaft and piston, of a cam rotatable by the shaft, means operable by the cam to control the exhaust valve and including a lifter element having a part removable to render said means inoperative, a switch controlled by said part to open and close the ignition system of the engine, and pressure controlled means arranged for uninterrupted communication with the compression chamber of the engine cylinder for replacing the removable part in said lifter element.

3. The combination with the exhaust valve on an internal combustion engine, the crank shaft and piston, of a cam rotatable by the shaft, means operable by the cam to control the exhaust valve and including spaced lifter elements and a spacing block insertible between the lifter elements to operatively connect the same, pressure controlled means communicating with the compression chamber of the engine for inserting the block between the lifter elements, a pair of contacts included in the ignition system of the engine, one contact carried by one element and the other contact carried by the block for opening and closing the circuit.

4. The combination with the exhaust valve on an internal combustion engine, the crank shaft and piston, of a cam rotatable by the shaft, means operable by the cam to control the exhaust valve and including spaced lifter rods slidably mounted, a spacing block pivotally carried by one rod for swinging between the rods to operatively connect the same, pressure controlled means for swinging the block communicating with the compression chamber of the engine, and governor means having a part engageable with one of the lifter rods to arrest the same.

5. The combination with the exhaust valve on an internal combustion engine, the crank shaft and piston, of a cam rotatable by the shaft, means operable by the cam to control the exhaust valve and including spaced lifter rods slidably mounted, a spacing block pivotally carried by one rod for swinging between the rods to operatively connect the

same, pressure controlled means for swinging the block communicating with the compression chamber of the engine, one lifter rod having a notch, and a governor for the engine having a part engageable in the rod notch to hold the rod positioned to prevent the block being inserted.

6. The combination with the exhaust valve on an internal combustion engine, the crank shaft and piston, of a cam rotatable by the shaft, means operable by the cam to control the exhaust valve and including spaced lifter rods slidably mounted, a spacing block pivotally carried by one rod for swinging

between the rods to operatively connect the 15 same, pressure controlled means for swinging the block communicating with the compression chamber of the engine, and a switch included in the ignition system of the engine and adapted to be opened and closed 20 by said pressure controlled means.

In testimony whereof I have hereunto set my hand in the presence of two subscribing witnesses.

HENRY C. MELVIN.
